Primary Examiner — John R Yeh*(74) Attorney, Agent, or Firm* — Duane Morris LLP(57) **CLAIM**

The ornamental design for a toilet brush assembly, as shown and described.

DESCRIPTION

FIG. 1 is an isometric view of our new design for a toilet brush assembly in a closed configuration; FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is an isometric view of our new design for a toilet brush assembly in an open configuration;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof;

FIG. 14 is a bottom plan view thereof; and,

FIG. 15 is an exploded isometric view of the toilet brush assembly. The broken lines in the figures depict portions of the toilet brush assembly that form no part of the claimed design.
